Patent expires February 11, 1966

7 Claims. (Cl. 128—423)

1

This invention relates to apparatus for electric therapy and more particularly to apparatus for use in producing convulsions in a subject by passing electric currents through the brain in, for example, the treatment of mental disorders.

Up to the present apparatus of the foregoing kind has essentially consisted of a step-down transformer suitable for direct connection to A.C. mains and a time switch device operable therewith to allow supply of a low frequency treating current for a predetermined period. The voltage range available for treatment was usually 50 to 150 volts and the duration of the treatment about 0.1 to 1 second. The patient was treated by being included in the electric circuit and since the impedance of the patient instantaneously varied, the total energy or dose could not be ascertained except by estimations relying upon such factors as voltage of supply and duration. Not only did the known apparatus suffer from this serious disadvantage, but moreover in convulsion therapy it is recognised that effective convulsing voltages depend on the initial few cycles in the sense that the voltage must be sufficiently high to produce the break-down effect, whereas subsequent cycles need not be of the same high voltage. Thus the known apparatus does not conform to the pattern of the desired treatment.

One object of the present invention is to provide apparatus in which the dosage in terms of supplied electrical energy can be readily ascertained and controlled, whilst affording treatment currents that conform to the pattern of the desired treatment, i. e. that are initially of high voltage with subsequent decrease. A further object of the invention is to provide apparatus which will permit use of bi-directional and/or uni-directional pulsating currents for the treatment.

In accordance with the invention treatment currents in electro-therapy apparatus of the kind hereinbefore referred to are produced with the aid of a condenser or condensers which can be charged to a known extent and then discharged in an oscillatory or interrupted manner to afford treatment currents of predetermined dosage value and at initially high, but decreasing, voltage.

For a better understanding of the nature of the invention a constructional embodiment thereof will hereinafter be described solely by way of example, with reference to the accompanying diagram.

In this constructional form a first condenser 11 and a second condenser 12 are employed. These however may be substituted by equivalent banks of condensers. Two double-pole changeover switches 13 and 14 operating as a 4 pole changeover unit are connected each with one of the con-

densers (or banks) so that each condenser is connected across a pair of movable switch arms which may be displaced into connection with either a first pair of fixed contacts 15 and 16 or a second pair of fixed contacts 17 and 18 in each switch. A potentiometer 19 forming part of a charging circuit for the two condensers 11 and 12 is connected across a source of direct current supply and the fixed contacts 15 and 16 are connected to said potentiometer. The nature of the connections of the fixed contacts 15 and 16 with the potentiometer are such that when the switch arms are co-operating with those fixed contacts the condensers are both charged at the potential determined by the variable tapping of the potentiometer.

A voltmeter 20 is preferably arranged to indicate the voltage as measured between the supply lines to the condensers when the latter are being charged and this voltmeter may be calibrated in joules so as to show the total electrical energy stored in the condensers.

The other two pairs of fixed contacts 17 and 18 of the change-over switches are connected with a treatment circuit including a first and second circuit. The second circuit includes the vibrating reed 21 of a vibrator arranged as a single pole change-over switch, there being a stationary contact 22 in the second circuit and a stationary contact 23 in the first circuit and a movable contact identifiable with the reed itself. The contact 18, connected with the positive plate of the condenser 12, is connected over conductor 26 of the second circuit with the one fixed contact 22 of the vibrator, whilst the other, connected to the negative, is connected over conductor 27 of the second circuit to an electrode-plate 24, a second electrode-plate 25 being connected to the reed of the vibrator. The patient is included in the circuit between the electrode-plates 24 and 25.

A double-pole change-over switch 30 forming part of the first circuit connects the condenser 11 in the first circuit, the one switch arm 33 being connected with the conductor 27 of the second circuit, whilst the other switch arm 34 is connected with the stationary contact 23 of the vibrator switch which is in the first circuit. The contacts 17 are simply connected with the switch 30 in such manner as to produce effective reversal of connections when said change-over switch is operated, i. e. to connect, for example, the positive plate of condenser 11 to the conductor 27, or to the fixed contact 23 of the vibrator.

In the use of the apparatus described the changeover switches directly associated with the condensers are brought first to the position where the condensers are charged. Thereafter they may be brought to the discharge position. The vibrator interrupts the discharge currents at the desired frequency. When the change-over

switch 30 is in one working position (in the upper position shown in the diagram) it causes discharge currents to be passed through the patient from both condensers 11 and 12 always in the same direction, the negative plates of both condensers being connected to the conductor 27. When the said switch 30 is, however, in its other working (or lower) position it causes the discharge currents from each condenser to pass through the patient in opposite directions. Thus bi-directional or uni-directional pulsating treatment currents are available. When the switch 30 is open and the four-pole change-over switch 13, 14 is in the position connecting the condensers to the first and second circuits, respectively, only condenser 12 will be discharged, condenser 11 being not connected to any closed circuit in this position of the switch 30.

The apparatus of the present invention thus enables convulsive currents to be produced, whose applied voltages are initially high but which rapidly fall to zero in a fraction of a second. Moreover, only a small amount of the electrical power is required to charge the condensers and the apparatus may be supplied from D. C. mains or from a battery.

I claim:

1. An electro-therapy apparatus comprising in combination, a first condenser; a second condenser; a first circuit; a second circuit connected to the terminals of said second condenser; a two-pole change-over switch inserted in said first circuit for connecting said first circuit selectively to the terminals of said first condenser; two electrodes adapted for connection to the patient, one of said electrodes being common to said first circuit and said second circuit; and a vibrating interrupter having a movable contact connected to the other of said electrodes and two stationary contacts connected, respectively, in said first circuit and said second circuit, whereby separate impulses from said two condensers may be applied selectively either unidirectionally or bi-directionally to the patient.

2. An electro-therapy apparatus comprising in combination, a first condenser; a second condenser; a charging circuit for said condensers; a first circuit; a second circuit; a four-pole change-over switch connecting said condensers to said charging circuit and to said first circuit and said second circuit, respectively; a two-pole change-over switch inserted in said first circuit for connecting said first circuit selectively to the terminals of said first condenser; two electrodes adapted for connection to the patient, one of said electrodes being common to said first circuit and said second circuit; and a vibrating interrupter having a movable contact connected to the other of said electrodes and two stationary contacts connected, respectively, in said first circuit and said second circuit, whereby separate impulses from said two condensers may be applied selectively either uni-directionally or bi-directionally to the patient.

3. An electro-therapy apparatus comprising in combination, at least one capacitor, a charging circuit for said capacitor; a treatment circuit; electrodes adapted to be applied to a patient in said treatment circuit; a periodically operating interrupter connected in said treatment circuit in series with said electrodes; and a switch for alternatively connecting said capacitor across said charging circuit and across said treatment circuit, whereby said capacitor can be first charged by said charging circuit and subsequently

discharged, the discharge current being periodically interrupted.

4. An electro-therapy apparatus comprising in combination, at least one capacitor, a charging circuit for said capacitor; a treatment circuit; electrodes adapted to be applied to a patient in said treatment circuit; a vibrating interrupter connected in said treatment circuit in series with said electrodes; and a switch for alternatively connecting said capacitor across said charging circuit and across said treatment circuit, whereby said capacitor can first be charged by said charging circuit and subsequently discharged, the discharge current being periodically interrupted.

5. An electro-therapy apparatus comprising in combination, two capacitors, a charging circuit for said capacitors; a treatment circuit having three branches with two terminals each; electrodes adapted to be applied to a patient in the first of said branches; a vibrator alternately connecting one terminal of the second branch and one terminal of the third branch to one terminal of said first branch; a first switching means connecting one of said capacitors alternatively across the charging circuit and the free terminals of the first and second branches of the treatment circuit; and a second switching means connecting the other capacitor alternatively across the charging circuit and the free terminals of the first and third branches of the treatment circuit.

6. An electro-therapy apparatus comprising in combination, two capacitors, a charging circuit for said capacitors; a treatment circuit having three branches with two terminals each; electrodes adapted to be applied to a patient in the first of said branches; a vibrator alternately connecting one terminal of the second branch and one terminal of the third branch to one terminal of said first branch; a first switching means connecting one of said capacitors alternatively across the charging circuit and the free terminals of the first and second branches of the treatment circuit; and a second switching means connecting the other capacitor alternatively across the charging circuit and the free terminals of the first and third branches of the treatment circuit, at least one of said switching means being adapted for reversal of polarity in either of their alternative connections.

7. An electro-therapy apparatus comprising in combination, at least one capacitor, a charging circuit for said capacitor; a potentiometer in said charging circuit controlling the charging voltage; a treatment circuit; electrodes adapted to be applied to a patient in said treatment circuit; a periodically operating interrupter connected in said treatment circuit in series with said electrodes; and a switch for alternatively connecting said capacitor across said charging circuit and across said treatment circuit, whereby said capacitor can first be charged by said charging circuit and subsequently discharged, the discharge current being periodically interrupted.
